UNITED STATES PATENT OFFICE.

WALTER C. CLIFFORD, OF SAN FRANCISCO, CALIFORNIA.

DETACHABLE HINGE.

1,192,989.

Specification of Letters Patent. Patented Aug. 1, 1916.

Application filed January 19, 1916. Serial No. 72,938.

To all whom it may concern:

Be it known that I, WALTER C. CLIFFORD, a citizen of the United States, residing in the city and county of San Francisco and State of California, have invented new and useful Improvements in Detachable Hinges, of which the following is a specification.

This invention relates to a detachable hinge.

10 One of the objects of the present invention is to provide a simple substantial, cheaply manufactured detachable hinge particularly adapted for use in connection with windows, shutters, doors and the like, and which is so 15 constructed that the window may be readily removed without unscrewing any part of the hinge or marring the casing to which it is attached, when it is desired to wash or dust the window, the shutter or other member carried by the hinge.

Further objects will hereinafter appear.

The invention consists of the parts and the construction and combination of parts as hereinafter more fully described and claimed, 25 having reference to the accompanying drawings in which—

Figure 1 is a disassembled view showing the hinge sections folded out. Fig. 2 is a horizontal transverse section and assembled 30 view of the hinge on line 2—2 of Fig. 1.

Referring to the drawings in detail A indicates a window casing, 2 a window-sash mounted therein, and 3, the hinge by which the sash is carried. The hinge proper forms 35 the subject matter of the present invention and is constructed as follows:

Referring to Fig. 1, 4 and 5 indicate the leaf sections of the hinge which are connected in the usual manner by the hinge 6 40 and a fixed pintle 7. The leaf section 5 is cut out as at 8 and the inner edge beveled as at 9 to form an interlocking member which will later be described. The inner edge of the leaf 5 is provided with a pair 45 of alined knuckles 10 adapted to receive the removable pintle 11. Adapted to be secured to the window-sash 2 by means of screws 12 is a comparatively small hinge leaf section 13 provided on its inner edge with a knuckle 14. This leaf is just sufficiently large to 50 snugly fit the cutaway portion 8 of the leaf 5 and the inner edge of the leaf 13 is beveled to fit the bevel 9.

In operation, when it is desired to place 55 the sash in position, it is accomplished by first securing the leaf 4 to the main casing

A by means of screw 15, and then securing the small leaf section 13 to the window-sash. The parts are now ready to be assembled and this is accomplished by placing the 60 sash in a position where the leaf 13 will enter the cutaway portion 8 of the leaf 5. It is now only necessary to insert the pintle 11 through the alined hinged sections 10 and the interposed hinge 14. The window may 65 now be closed to assume the position shown in Fig. 2 and may be opened in the usual manner about the hinge 3. The beveled edges indicated at 9 formed between the leaf sections 5 and 13 produces an interlock 70 between said leaf sections which prevents movement of one with relation to the other. The leaf sections 5 and 13, when the sash is in position, will thus act as a single leaf of a hinge and will therefore permit 75 the sash to be swung about the hinge 3 similar to an ordinary hinge. If it is desired to remove the sash when washing, dusting or for other purposes, it is only necessary to remove the pintle 11, a head or knob 16 being formed on the upper end of the pintle 80 to permit it to be easily removed. The removal of the pintle 11 permits the leaf section 13 to be removed from the leaf 5 and the sash can therefore be removed to any 85 convenient point for window washing or for any other purpose.

A hinge constructed as here shown, is simple and substantial of construction, it permits the use of a fixed pintle 7 on the exterior side of the window and a removable pintle on the interior side. The hinge is in this manner burglar-proof and at the same time provides a means whereby the sash may be removed at any time without unscrewing 95 any of the hinge or leaf sections or otherwise marring the sash or casing.

The materials and finish of the several parts of the hinge may be such as the judgment and experience of the manufacturer 100 may dictate.

I wish it understood that various changes in form, proportion, and minor details of construction may be resorted to within the scope of the appended claims and that I do 105 not wish to limit myself to the specific design and construction here shown.

Having thus described my invention, what I claim and desire to secure by Letters Patent is—

110 1. A detachable hinge comprising a pair of hingedly connected leaf sections, one of

said leaves having a pocket formed therein to receive a removable leaf and the other leaf being adapted to be secured to a support, means for securing the removable leaf 5 to a member to be supported, and means for securing the removable leaf in the pocket of the first named leaf.

2. A detachable hinge comprising a pair of hingedly connected leaf sections, one of 10 said leaves having its central portion cut away as described to form an inner beveled edge and pocket for the reception of a removable leaf section, a beveled edge on one side of the removable leaf adapted to interlock with the first named beveled edge, a hinge on the opposite side of the removable 15 leaf, a pair of alined hinge members on the first named leaf with which the removable leaf hinge is adapted to register, and a pintle adapted to be inserted through the said 20

alined hinge members to secure the removable leaf, or adapted to be removed to release the removable leaf.

3. The combination with a hinge having one leaf cut out to form a pocket therein, of 25 a removable leaf insertible in said pocket and adapted to assume a position where the top and bottom surfaces of the leaves lie parallel and means for securing the insertible leaf against removal, said means comprising a removable pintle adapted to be inserted through one end of the cut out leaf and the insertible leaf. 30

In testimony whereof I have hereunto set my hand in the presence of two subscribing 35 witnesses.

WALTER C. CLIFFORD.
